UNITED STATES PATENT OFFICE.

LORENZA DOW McDONALD, OF ATLANTA, GEORGIA.

LIFE-PRESERVER.

No. 916,761.

Specification of Letters Patent. Patented March 30, 1909.

Application filed August 22, 1908. Serial No. 449,831.

To all whom it may concern:

Be it known that I, LORENZA D. McDONALD, a citizen of the United States, residing at Atlanta, in the county of Fulton and State of Georgia, have invented certain new and useful Improvements in Life-Preservers, of which the following is a specification.

This invention relates to life preservers, more particularly to the pneumatic type and has for its purpose such an article embodying a plurality of air chambers or floats independently and detachably carried by a belt.

Another object is to provide a life preserver that may, with slight changes in the arrangement of its parts be adapted for use as an aid to swimming.

The further purpose of the invention is in providing the belt with appurtenances that will insure absolute safety in correctly holding the life preserver to the body.

With these and other objects in view which will be pointed out in the course of the specification and set forth in the claims, my invention is shown in its preferred embodiment in the accompanying illustration wherein,

Figure 1 is a perspective view of the life preserver complete, Fig. 2 illustrates its manner of application, and Fig. 3 is a detail of a contemplated modification that may be used.

Referring more in detail to the several figures shown wherein like reference characters designate corresponding parts in the different views A is a belt of the ordinary kind provided with the usual buckle B. At suitable points on the belt A is a number of independent air-tight metallic floats C, preferably constructed of copper, but of course they may be made of any other suitable non-corrosive metal. The floats are each provided with a valve H whereby they may be filled with any light gas. Said floats are likewise provided with a strap e riveted or otherwise secured to the bottom thereof, and through each of said straps is a ring D by means of which the several independent floats may be movably attached to the belt. In the illustration shown the rings D are preferably threaded or strung upon a belt A, as this manner of attachment permits of their being moved to any position

upon the belt when for any reason such should be desired. As an instance of this the user of the device may desire to move such floats as would interfere with his arms in swimming in which case the interfering floats 55 may be moved or slid to the back of the belt in which position the device would serve its full purpose as a float and yet permit the wearer thereof freedom of his limbs.

To positively hold the belt in proper position about the waist of the wearer a pair of side straps E is provided which straps are hung from the belt by rings D' carrying snap-hooks F. The straps E are designed to encircle the legs of the wearer in the manner 65 shown in Fig. 2. A pair of auxiliary sliding rings G having snap-hooks is provided on the belt A, whereby the position of the leg straps E may be changed.

The belt A may be provided with a plurality of pockets I, as shown in Fig. 3, in which may be placed the valuables of the wearer. In this view is also shown a modification of the air-tight floats, differing in that the valve H of C' is adjacent the securing member D' 75 as distinct from that shown in the floats C.

What is claimed as new is:

A life preserver comprising a belt, a plurality of rings threaded on said belt and adapted to have free and independent movement 80 thereon, each of said rings having an independent air-tight float loosely secured thereto, said floats normally depending from said rings but adapted to assume an upright position when the life preserver is in use, a pair of 85 detachably looped straps secured to said belt by rings adapted to have sliding movement thereon, said looped straps adapted to encircle the legs of the wearer whereby said belt is held in proper position, a pair of auxiliary 90 sliding rings on said belt, whereby the position of said straps may be changed, and means whereby said belt may be adjusted to the waist of the wearer.

In testimony whereof I affix my signature 95 in presence of two witnesses.

LORENZA DOW McDONALD.
